TRAVEL EXPENSE RECORDER

Philip M. Tubbs, 78 Gorham St.,
Canandaigua, N.Y. 14424

Filed Aug. 23, 1966, Ser. No. 3,562

Term of patent 3½ years

(Cl. D52—1)

Fig. 1

Fig. 2

Fig. 3

Fig. 4

FIG. 1 is a perspective view of a travel expense recorder, showing my new design;

FIG. 2 is a side elevational view thereof;

FIG. 3 is a front elevational view thereof; and

FIG. 4 is a rear elevational view thereof.

The side opposite to that illustrated in FIG. 2 is substantially a reverse duplicate of the side shown in FIG. 2.

I claim:

The ornamental design for a travel expense recorder, substantially as shown and described.
